UNITED STATES PATENT OFFICE

130,564

DESIGN FOR A PORTABLE TRAFFIC SIGNAL

J. Stuart Bicknell, Clare, Mich., assignor to J. Stuart Bicknell, Mark H. Bicknell, Harold Hanchett, and W. James Olson, Clare, Mich., a partnership

Application May 15, 1941, Serial No. 100,948

Term of patent 14 years

To all whom it may concern:

Be it known that J. Stuart Bicknell, a citizen of the United States of America, residing at Clare, in the county of Clare and State of Michigan, has invented a new, original, and ornamental Design for a Portable Traffic Signal, of which the following is a specification, reference being had to the accompanying drawing, forming a part thereof, wherein:

Fig. 1 is a perspective view of a portable traffic signal embodying my new design; and

Fig. 2 is a top plan view of the same.

I claim:

The ornamental design for a portable traffic signal, substantially as shown.

J. STUART BICKNELL.
